UNITED STATES PATENT OFFICE.

PHILIP JOHN KNORPP, OF BROOKLYN, NEW YORK, ASSIGNOR TO N. D. Q. SPECIALTY CORPORATION, OF BROOKLYN, NEW YORK, A CORPORATION OF NEW YORK.

DISPLAY HOLDER.

Application filed July 29, 1925. Serial No. 46,741.

This invention relates to a display holder. The sales of many small articles can be enhanced if displayed in the stores.

One of the objects of this invention is to provide a display holder that will effectively hold and display articles to be sold. Further objects of this invention are to provide a display holder that will be inexpensive to manufacture, light in weight, but strong and of good appearance. Still other objects are to provide a display holder that can be stacked and easily shipped with the merchandise and which will protect it while in shipment.

15 Referring to the drawings:

Figure 1 is a view in perspective of a device embodying the principles of my invention.

Figure 2 is a view in section of a number 20 of my devices stacked for shipment.

In carrying out my invention, I preferably propose to make the display holder 1 of sheet metal in one piece except that a foot or back piece 4 is riveted or secured in any well known manner to the back of body portion 3 of the display holder to support it.

The display holder 1 has top piece 2 upon the face of which can be placed advertising matter. Below top piece 1 is body portion 3 bent to hold a carton or other container in which are the articles to be sold. The angle between the back and the top and bottom sides of body portion 3 is slightly less than a right angle in order that the body portion 35 can grip the carton or container. Below body portion 3 is bottom 5, upon which the front of the display holder rests and which causes it to tilt back and rest upon the bot-

tom edge of body portion 3, the back piece 4 acting as an additional support to lend it greater stability. The carton containing the articles to be displayed generally has a glass cover but should it have a cardboard cover it should be removed. In operation the carton is placed in the body portion 3. In doing so the top piece 2 and the bottom piece 5 must be sprung slightly to permit the carton to be inserted. Back piece 4 is then bent to the proper angle to body portion 3 and the display cabinet can be set up on the counter. In shipment, the carton is placed in body portion 3 with the glass cover facing inwards in other words, adjacent the body portion and protected thereby.

In shipment the container stacks, see Figure 11, the back portion 4 being bent to rest flat against body portion 3.

What I claim is:

A display holder having top and bottom portions and a body portion, said body portion adapted to hold in frictional engagement a container, top and bottom sides to said body portion, said top and bottom sides extending the thickness of the top and bottom portions beyond said container to permit of stacking and to protect the container in shipment, and a flat support secured to said body portion to support the display holder at an angle to the vertical, said flat support adapted to be bent back to rest flat on the back of the body portion to permit of stacking and shipment.

Signed at Brooklyn, in the county of Kings and State of New York this 20th day of July, A. D. 1925.

PHILIP JOHN KNORPP.
